UNITED STATES PATENT OFFICE.

HARRY B. EATON, OF TAUNTON, MASSACHUSETTS, ASSIGNOR TO U. S. BOBBIN & SHUTTLE COMPANY, OF MANCHESTER, NEW HAMPSHIRE, A CORPORATION OF RHODE ISLAND.

APPARATUS FOR USE IN THE HEAT TREATMENT OF METAL.

Application filed March 22, 1922. Serial No. 545,880.

To all whom it may concern:

Be it known that I, HARRY B. EATON, a citizen of the United States of America, and resident of Taunton, in the county of Bristol and State of Massachusetts, have invented new and useful Improvements in Apparatus for Use in the Heat Treatment of Metal, of which the following is a specification.

- 10 This invention concerns hardening and tempering furnaces and relates more particularly to means whereby the material to be heat-treated may be introduced into the furnace for heating and withdrawn therefrom
 15 for quenching without undue exposure of the material to the air, either during its heating or during its transfer from the furnace to the quenching bath, while at the same time avoiding undue waste of heat
 20 from the furnace during the introduction and withdrawal of the charge.

In the heat treatment of steel for hardening or tempering it, it is necessary to raise it to a temperature at which oxidization of the metal takes place very rapidly if freely exposed to the air. If the period of exposure is at all prolonged under such circumstances a very substantial amount of metal may be converted into oxide. This action is particularly harmful when the article to be treated is relatively small or comprises parts which are thin or of small diameter, as for example, metallic bobbin rings, spring washers, etc. In such cases so much of the material may be converted into oxide that the finished article may be of little commercial value, thus necessitating the making of the article heavier than desired, originally, so that after hardening, sufficient metallic steel will remain to provide the desired strength. This practice is wasteful of material and labor, and in many cases is wholly impracticable.

Hardening furnaces of large capacity consume a very considerable amount of heat and when electricity is employed as a heating agent, it is especially desirable, for the sake of economy in operation, to avoid so far as practicable, the escape of heat from the heating chamber during the introduction and withdrawal of the charge.

Various types of furnace and apparatus for

the heat treatment of steel have heretofore been devised, some of which are automatic or continuous in operation, but so far as is known no serious attempt has been made heretofore to design heat-treating apparatus of a character such as to permit the ready handling of relatively small articles in large quantities and so arranged as substantially to lessen the oxidization of the material during the treatment, or to conserve the heat supplied for bringing the material to the desired temperature.

The object of the present invention is accordingly to provide improved means useful in association with furnaces of usual construction for introducing the charge of material to be treated into the furnace in a manner permitting the rapid and uniform heating thereof and for withdrawing it quickly therefrom while avoiding the exposure of the heated charge to unlimited amounts of atmospheric oxygen, either during the heating thereof or in its transfer to the quenching bath, and at the same time reducing the loss of heat from the furnace to a minimum during the operation.

In the attainment of the above object, an arrangement of parts such as is shown in the accompanying drawings may be employed, such arrangement well exemplifying the various embodiments of means which might be employed for the purpose.

In such drawings:—

Figure 1 is a side elevation of a furnace having the apparatus of the present invention applied thereto;

Figure 2 is a cross section on a line *a*—*b* of Fig. 1, but to larger scale, showing the charging and discharging apparatus in position for receiving a charge of material;

Figure 3 is a view similar to Fig. 2 but showing the parts in position for dumping the heated material;

Figure 4 is a cross section to large scale on the line *c*—*d* of Fig. 1, showing the furnace construction;

Figure 5 is a transverse cross section on a line such as *e*—*f* of Fig. 1, showing certain controlling mechanism, this view being to somewhat larger scale than Fig. 1;

Figure 6 is a longitudinal cross section through the charging and discharging ap-

paratus and the controlling mechanism therefor showing one end only of the furnace and drawn to large scale;

5 Figure 7 is a longitudinal cross section, partly in elevation, illustrating a quenching tank employed in connection with the apparatus, and automatic mechanism for removing the quenched material from such tank;

10 Figure 8 is a vertical cross section on the line *r-s* of Fig. 7, and showing the furnace and charging and discharging apparatus in broken lines;

15 Figure 9 is a cross section on the line *g-h* of Fig. 7 but to larger scale;

Figure 10 is a similar cross section on the line *m-n* of Figure 7;

20 Figure 11 is a fragmentary front elevation of a switchboard having switches thereon for controlling certain of the appliances herein disclosed;

Figure 12 is a fragmentary cross section on the line *o-p* of Fig. 11;

25 Figure 13 is a fragmentary cross section on the line *x-y* of Fig. 5; and

30 Figure 14 is a top plan view of a guard for the charge receptacle, together with means for imparting movement thereto; the charge receptacle, with the guide means therefor, being omitted, and a portion of the guard being broken away.

Referring to the drawings a furnace is indicated at 1, the furnace herein illustrated being typical of any desired type of furnace 35 which may be found useful in carrying the hardening operation into effect. This furnace rests upon the piers 2, 3, and comprises the outer metallic casing 4 having the bottom wall 19 and the inner refractory lining 5, 40 the lining being separated from the outer casing, and the space therebetween being filled with suitable heat insulating material 6, such for example, as asbestos, mineral wool or the like. The heating chamber 7 45 extends longitudinally of the furnace and is provided with a plurality of insulating supports 8 having wound thereon electrical resistance coils 9, such coils being suitably connected to bus-bars 10, mounted upon 50 insulating brackets such as 11 upon the outer wall of the furnace. If desired this bar may be enclosed by a protecting casing 12. The several supports 8 are of such a form as to provide an inner chamber 13 55 of a size suitable to admit the receiver for the charge to be heated. Extending along the bottom of this inner chamber is a pair of guide rails 14, 15, respectively or equivalent devices, spaced apart to provide a guide slot 16. These rails, if desired, may have 60 downwardly extending members such as 17 rigidly secured in place in any desired manner and preferably having heat insulating material 21, for example asbestos or 65 mineral wool interposed between them.

Transverse brace rods 20 may be employed for holding the upper portions of the members 17 in properly spaced relation, and between the members 17 insulating material such as asbestos or mineral wool, indicated 70 at 21, may be employed.

The end wall 22 of the furnace is provided with a charging opening 22^a with which cooperates a sliding door 23 suitably guided by means of flanged members such 75 as 24. To this door is secured the lower end of the cable 25, which passes over a pulley 26, thence longitudinally of the apparatus to a pulley 27 mounted at the upper end of a switchboard 28, and thence 80 downwardly along the face of the latter, such cable being provided with a hand grip 29 at a suitable point whereby the cable may be manipulated to raise the door of the furnace to permit the entrance or exit 85 of a charge.

Associated with the furnace, and arranged in longitudinal alignment therewith, and in a position to hood the door thereof, is the charging and discharging housing or casing 30. This housing or casing is of generally rectangular cross section, comprising the side wall 31, top wall 32, and the opposite side wall 33 (the latter having its lower portion 34 inclined downwardly), 90 and having a discharge opening 35 extending between the lower edge of the wall 31 and the lower edge of the inclined wall member 34. Hinged to the lower edge of the latter, at the point 36 is a door 37 which normally occupies the position indicated in Fig. 2, thus completely closing such discharge opening and constituting the bottom wall of the housing. The walls of this housing, with the exception of such 95 bottom wall, and the closure for a receiving opening, hereinafter described, preferably consist of inner and outer metallic casings such as 38, 39, spaced apart and insulated from one another by a packing of heat insulating material 40. This material may be asbestos fibre, mineral wool, or any other desired heat insulating and heat resistant medium. This housing 30 may be secured at one end directly to the end wall 22 of 100 the furnace and at its opposite end may be supported upon legs such as 41 or in any other desired manner. The upper wall 32 of this housing is provided with a receiving opening of elongate form extending longitudinally of the housing substantially 105 from one end to the other thereof. The edges of the top wall 32, at opposite sides of this opening, are inclined downwardly and inwardly as indicated at 42, and to the lower edges of such opening, upon opposite sides thereof, are hinged doors 44, 45. These doors are so arranged that when in 110 closed position, as shown in Fig. 3 they overlap somewhat, thereby completely clos- 115

ing the opening and preventing the escape of heated gases therethrough. When in closed position, these doors, with the inclined edges 42, form a depression, cavity 5 or recess 43 in which material to be treated may be piled.

Secured to the wall 32 along the edges of the receiving opening are brackets such as 46 and 49, and in said brackets are journaled rods 48 and 47, respectively. To these rods, at intervals, are secured arms 50 which in turn are connected to the respective doors 44, 45 by means of links 52, 53 respectively. The ends of the rods 48 and 47, extend beyond the end wall 54 of the housing 30, and to the rod 48 is secured an actuating lever 55. To the rod 47 is secured a lever arm 56 which is connected by means of a link 57 to a lever arm 58 also secured to the rod 48. The link 57 is connected to the arm 56 by means of a pin engaging a slot 59 in such arm, and the parts are so arranged that upon actuation of the lever 55 the rods 48 and 47 are rotated simultaneously, but in opposite directions. Any suitable means may be employed for holding the lever 55 in desired position of adjustment.

Journaled in a bracket 60 secured to the end wall 32 of the furnace and below the door, therein, is one end of a shaft 61, the opposite end of such shaft being journaled in a bracket 62 secured to the end wall 54 of the housing 30. To the end of the shaft 61 where it extends beyond the bracket 62 is secured an arm 61^a ending in an abrupt shoulder at 69. To the side of this arm a lever 63 is secured, forming a continuation of the arm 61^a, such lever being provided with an actuating handle 64 at its outer end. A latch lever 65 is pivotally secured at the point 66 to a bracket member 67 secured to the housing 30, such latch lever having a latch shoulder 68 engageable with the shoulder 69 of the arm 61^a. A spring 70 is normally operative to hold the latch shoulder 68 in engagement with such shoulder whereby to hold the lever arm 63 in the position shown in Fig. 5 and with the shaft 61 occupying the position indicated in Fig. 2.

A series of brackets 71 are secured at spaced intervals to the under side of the shaft 61, such brackets having members extending upwardly and in divergent relation 55 upon opposite sides of the shaft. Resting upon and in recesses in the upper side of this shaft is a trough-shaped guard member comprising the bottom wall 72 and the divergent side walls 73, 74, respectively. The divergent members of the brackets 71 are secured, as by means of rivets, to the diverging side walls of this trough-shaped guard member. Such guard member extends substantially from one end of the housing 30 to the other and secured to the upper surface

of the bottom wall 72 thereof are substantially parallel rails 75, 76, these rails being spaced to provide a guide slot 77. The rails 75, 76, are preferably of channel form as indicated in Fig. 2 for a purpose herein-after to be described. Slidably engaging the slot 77 is a rectangular bar 78. This bar, and such of the other parts as may be exposed to the heat of the furnace, may be of "nichrome" or some similar heat resistant material. Secured to the bar 78 is a charge holding receptacle or receiver 79, such receptacle comprising the bottom wall 80 and the divergent side walls 81, 82. The receptacle is preferably spaced somewhat from the guard member previously described, and is retained in proper position when the shaft 61 is rocked, as seen in Fig. 3, by means of straps 79^a extending over the receptacle and secured to the opposite edges of the guard device. This receptacle is of large surface area and relatively shallow in order that the charge of material placed therein may rapidly be heated when introduced into the furnace. The arrangement of the shaft 61 and the guide rails 75, 76, is such that when the parts occupy a position such as indicated in Fig. 2, the slot 77 between such rails aligns with the slot 16 between the rails 14, 15 within the furnace heating chamber so that the bar 78 with the charge receiver 79 may readily be slid into the furnace through the door 22. To the wall 74 of the guard member, lugs 83 are secured, to which are connected the upper ends of tension springs 84, the lower ends of which are secured to links 85 pivotally connected to brackets 86 secured to the door 37, the parts being so arranged that upon rocking of the shaft 61 to bring the parts from the position of Fig. 3 to that of Fig. 2, this spring will be tensioned, thereby resiliently holding the door 37 in closed position. The provision of the guard trough immediately below the receptacle serves effectively to guard the heated contents of the receptacle from drafts of air which may enter the housing 30 as the door 37 is opened.

Upon the back side of the switchboard 28 is secured a bracket 87 having mounted thereupon an electric motor 88 having a shaft 89 provided with a worm 90 meshing with a worm wheel 91 upon a shaft 92. Mounted upon this shaft is a drum 93 over which passes a cable 94, the upper run 95 of which is secured to a bracket 95^a mounted upon the outer end of the bar 78, such end projecting out through a suitable opening in the end wall 54 of the housing. The lower run 96 of the cable is secured at 97 to a floating pulley 98. A second cable is passed about the pulley 98, such cable comprising the runs 99, 100, respectively, which pass about a pair of pulleys such as 101, secured to the under side of the guard member at that end thereof adja-

cent to the furnace door. These runs 99, 100 of the cable then pass forwardly in the channels of rails 76, 75 respectively, toward the end 54 of the housing 30 and are secured 5 as indicated at the points 102, 103 respectively to the bracket 95^a upon the end of the rod or bar 78. With the parts as thus arranged, rotation of the motor driven drum 93 in either direction serves to impart movement to the bar 78 in one direction or the other in accordance with the direction of movement of the drum.

Pivottally mounted upon the front face of the switchboard are a pair of knife switches 104, 105 having suitable operating handles, one of such switches serving to set the motor in rotation in one direction and the other of such switches acting to reverse the motor. A bar 106 is suitably guided, as by means 20 of brackets 107, for vertical movement along the face of the switchboard, such bar being provided with a weight 108 at its lower end if desired. This bar is furnished with a pair of lugs 109, 110, respectively, which in 25 certain positions of the bar lie in the path of movement of bracket members such as 105^a carried by the respective switches, such lugs serving to prevent closing of the switches when the lugs are thus positioned. 30 Each of the switches is provided with a tail member 110, 111 respectively, such members being provided with slots 112, 113. The upper and lower runs 95 and 96 of the cable 94 which passes about the drum 93, extend 35 through the respective slots 112, 113, and to such runs of the cable are secured buttons, as 114, these buttons being of a diameter such that they will not pass through the slots in the tail members of the switches. 40 At one side of, and somewhat below the casing 30, a quenching tank 115 is arranged, this tank being of the cross section indicated in Fig. 8 and having the sloping side wall 116. This side wall is so positioned that when the door 37 is swung downwardly to open position, as indicated in dotted lines in Fig. 8, the lower edge of such door engages the inner surface of the inclined wall 116 of the tank so that the 45 charge of material, in dropping through the discharge opening in the casing 30, is directed into the quenching bath contained within the tank. This tank is provided with an upwardly sloping bottom as indicated at 117 (Fig. 7), and continuing upwardly in substantial alignment with said bottom is a trough-like structure 118, such structure terminating at a point adjacent to the furnace and substantially above the 50 floor 119 upon which the furnace is set. At the upper end of this trough 118 is arranged a receptacle 120 into which the material, after hardening, may be delivered. The lower edge of the tank is of curved cross 55 section, as indicated at 121, and the trough 60

118 is curved correspondingly. These curved portions of the tank and trough serve for the reception and guidance of a series of scraper disks 122 carried by an endless chain 123. This chain is trained 70 over guide sprockets 124, 125 and 126, and over a drive sprocket 127, the latter receiving its motion from a belt 128 passing about a pulley 128^a. The scraper disks 122 are preferably formed with recesses or notches 75 129 in their edges in order to permit the free escape of oil between the edges of the disks and the trough in which the disks move. The upper run of the endless chain carrying the scraper disks is substantially 80 horizontal and beneath such horizontal run of the chain is arranged a drip trough 130, such trough, if desired, being inclined somewhat toward the sprocket 124 and being provided with a downward continuation 131 85 which serves to direct oil from the trough into the tank 115. Beneath the trough 118, which is provided with series of drain openings 132, is arranged a drip trough 133 which is inclined downwardly and delivers 90 oil into the rear end of the tank 115. If desired, steam coils such as 134, 135 may be associated with the trough 118, such coils being supplied with steam through a pipe 136 controlled by a valve 137 and serving 95 to warm the trough 118 so that oil carried upward by the material in its movement from the tank will be heated and made sufficiently thin to drain rapidly from the material.

In the operation of the device described, it being assumed that the furnace door 23 is closed, that the charge receiver has been tipped to the position shown in Fig. 3 to dump the preceding load, and that a fresh charge of material has been piled in the recess 43 upon the doors 44, 45, the first step is to tilt the shaft 61 by means of the lever handle 64 whereby to restore the receiver to the position of Fig. 2. In tilting the shaft 61 to the position of Fig. 2 the upward movement of the guard element 74 tensions the spring 84, thereby closing the door 37. The operator then manipulates the handle 55 to open the doors 44 and 45, thereby dumping the material which has been piled in the recess or depression 43 into the charge receiver, which now occupies the position of Fig. 2. The bar 106 occupies the position shown in Fig. 11 when the furnace door 23 is closed, and in this position of the parts it is impossible to throw either of the switches 104, 105. After the dumping of the charge and the closing of the doors 44, 45, the operator pulls down upon the hand grip 29, thereby lifting the furnace door and opening communication between the casing 30 and the heating chamber of the furnace. The movement of the hand grip 29 permits the bar 106 to 100 105 110 115 120 125 130 135

descend to a distance sufficient to remove the lugs 109, 110 from beneath the switch brackets 105. The operator then closes the switch 105, this movement being permitted 5 by reason of the fact that the button 114 carried by the lower run 96 of the cable stands at a distance from the tail of the switch, as shown in Fig. 12. At this time, however, the button carried by the upper 10 run 95 of the cable occupies such a position that the closing of the other switch is impossible. Upon closing of the lower switch, the motor is actuated, drawing upon the run 96 of the cable and thereby, through 15 the cable 99, causing the bar 78 to move toward the furnace. The movement of the bar 78 thus causes the charge receiver to enter the furnace, it being noted that by reason of the connection of both cables to the 20 outer end of the bar 78, such connection is not subjected to the heat of the furnace at any time. When the charge receiver has been properly positioned within the furnace, the button 114 comes into contact with the 25 tail of switch 105 thereby automatically opening the switch. The operator then manipulates the handle 29 to close the furnace door, restoring the bar 106 to the position of Fig. 11 where manipulation of 30 either switch is prevented. During the introduction of the charge receiver into the furnace, the button 114 carried by the cable run 95 moves away from the tail of the upper switch, so that closing of such 35 switch is now prevented only by the lug 109 of bar 106. After the charge has remained in the furnace for the proper length of time, the furnace door is again opened, thereby depressing bar 106 and permitting 40 the actuation of switch 104. Upon closing of the switch, the motor is operated in the reverse direction, thereby drawing directly upon the upper run 95 of the cable and pulling the charge receiver outwardly from 45 the furnace and into the casing 30. At the end of a predetermined movement, the button 114 carried by cable run 95, contacts with the tail 110 of the upper switch, thereby throwing the latter out and stopping 50 the motor. The operator now closes the furnace door to prevent escape of heat and manipulates the handle 64 for rocking the shaft 61, thereby simultaneously opening door 37 and dumping the charge from the 55 charge receiver. The charge of heated material passes downwardly (the inclined wall 34 of the housing serving, if need be, to direct the material toward the discharge opening) and directly into the tank 115 60 where it is quenched by an oil bath or other suitable quenching medium. As the material falls to the bottom of the tank, it is scraped therefrom by the constantly moving scrapers 122, moved upwardly while 65 being drained, and dropped into the recep-

tacle 120. Upon dumping the charge receiver, the parts are in position for a subsequent series of operations such as above described.

In the above operation it will be noted 70 that the charge, after entering the casing 30, is never subjected to the action of free or unlimited amounts of air during the heating and quenching of the same, while it is also to be noted that the insulated 75 housing or casing 30 serves in large measure, not only to prevent the escape and loss of heat from the furnace door, but to prevent entry of air thereinto. The interior of this casing becomes very hot after a short period 80 of operation, so that there is but little drop in temperature of the charge as the latter is removed from the furnace and prior to its dumping through the discharge door of the casing. Under some circumstances, in 85 order to avoid any loss whatsoever in temperature, it may be desirable to supply the casing 30 with heating elements such as employed in the furnace proper, or other heating means such as may be found desirable. When used for the tempering of 90 relatively small articles such for example as bobbin rings, this device is particularly advantageous in that a relatively large amount of material may readily be placed 95 in the charge receiver, which is of a superficial area such as to permit exposing all the material to a substantially uniform heat whereby the heating of the same is accomplished rapidly and without fear of overheat- 100 ing some parts of the mass. At the same time, by providing the casing 30 and the guard device immediately below the charge receiver the entire mass of material 105 is protected against drafts or substantial drop in temperature during the removal of the same from the furnace, although such removal may occupy a considerable period of time due to the size of the container, while the arrangement whereby the entire 110 charge may be dropped instantaneously into the quenching bath assures uniform hardening of the entire mass of material, and at the same time avoids any tendency injuriously to oxidize the thinner portions thereof. 115 While the present improvements have been shown as applied to a furnace of the electrically heated type, it is contemplated that it might well be used in connection with furnaces of other forms and while a specific arrangement has been illustrated herein, whereby material after hardening is removed from the quenching bath, such arrangement is shown merely by way of example of suitable means for performing such 120 operation. Although specific arrangements have been shown for moving the charge receiver in and out of the furnace, it is to be understood that other arrangements might well be substituted for those herein 125 130

disclosed, and that various changes and rearrangements in the parts might be made without departing from the spirit of the present invention and without substantially changing the function of the apparatus.

What I claim and desire to secure by Letters Patent of the United States is:

1. In combination with a furnace structure, a quenching tank, means for conveying 10 a charge from the furnace to such tank, and heat insulated means for enclosing said conveying means during the movement of the charge between the furnace and the quenching tank.
- 15 2. Apparatus for use in the charging of furnaces comprising a heat insulated housing having a door at one end for communication with a furnace, said housing having a depression in its upper wall, and movable 20 means normally constituting a floor for such depression.
- 25 3. A furnace charging apparatus comprising an elongate, box-like housing having a depression in its upper wall, a pair of normally closed doors hingedly secured to said wall at opposite sides of said depression and constituting a floor therefor, and means for opening said doors.
- 30 4. A furnace charging apparatus comprising a housing having insulated walls, a recess in the thickness of the upper wall thereof, a pair of doors normally constituting the floor of said recess, said doors being hinged to swing downwardly into the housing, and 35 means for simultaneously opening said doors.
- 35 5. A furnace charging apparatus comprising an insulated housing having an elongate recess in the thickness of its wall, a pair of doors hinged at opposite edges of said recess, respectively, and normally constituting the floor of the latter, a rotatable rod supported adjacent to each edge of the recess, connections between said rods and the respective 45 doors such that upon rotation of the rods the doors are actuated, and means for imparting simultaneous movement to said rods.
- 45 6. A furnace charging apparatus comprising a housing having a recess in its upper 50 walls, a pair of doors hinged respectively adjacent to opposite edges of said recess and normally constituting a floor therefor, an actuating lever, and connections between said lever and the respective doors so constructed and arranged that upon actuation of the lever, the doors are simultaneously swung for opening or closing said opening.
- 55 7. An apparatus of the class described comprising a box-like housing having elongate openings in its top and bottom walls, a pair of overlapping doors normally closing the opening in the upper wall, and a downwardly swinging door normally closing the opening in the lower wall.
- 65 8. An apparatus for use in charging and discharging furnaces comprising a housing having a receiving opening in its upper wall, a delivery opening in its lower wall, a downwardly inclined deflecting surface leading to said lower opening, and a door normally closing said opening.
9. A furnace charging and discharging apparatus comprising an elongate housing having a substantially horizontal upper wall provided with a receiving opening, an inclined side wall leading to a discharge opening at the bottom thereof, and a door for closing the latter opening.
- 10 10. A furnace charging and discharging apparatus comprising an elongate housing of generally rectangular cross section, the lower portion of one of the side walls thereof inclining inwardly toward the opposite wall, and the top wall of said housing having a receiving opening, the housing having a discharge opening at the lower edge of the aforesaid inclined portion of the side wall.
- 10 11. An apparatus of the class described comprising a housing having a door for communication with a furnace, a discharge opening at its lower portion, a door for closing said opening, means for controlling the door, and resilient means normally holding said door in closed position.
- 10 12. An apparatus for use in charging and discharging furnaces comprising a housing having a discharge opening at its lower portion, a door for controlling said opening, an oscillatable element associated with said housing, and spring means connecting said element with the door whereby normally to hold the latter in closed position.
- 10 13. An apparatus of the class described comprising a housing having a discharge opening, a door for closing said opening, an oscillatable charge container within said housing, and means movable in timed relation to the oscillation of said container for opening and closing said door.
- 10 14. Apparatus for use in charging and discharging furnaces comprising a housing having a discharge opening therein, a door for controlling said opening, oscillatable charge supporting means within the housing, and connections including a tension spring, interposed between said oscillatable means and the door.
- 10 15. An apparatus of the class described comprising a housing having openings at its upper and lower parts respectively, a charge receiver within the housing, and movable means for supporting said receiver, said means being constructed and arranged to permit the introduction of a charge into said receiver through the upper opening, and its discharge from the receiver through the lower opening.
- 10 16. A furnace charging and discharging apparatus comprising a housing having a discharge opening at its lower portion, a

hinged door for closing said opening, a tilt-
able charge receiver within the housing,
normally tensioned resilient means opera-
tive to hold said door closed, and means
5 movable, upon tilting of the charge receiver
for dumping the load, to relieve the tension
upon said resilient means whereby to per-
mit said door to open.

17. A furnace charging and discharging
10 apparatus comprising a housing having a
discharge opening, a hinged door for clos-
ing said opening, a tilttable charge receiver
within the housing, a member movable with
said receiver, and resilient connections be-
15 tween said member and the door, the parts
being so constructed and arranged that upon
movement of the receiver from dumping to
receiving position, such resilient connections
will be tensioned to close the door.

20 18. An apparatus for use in charging and
discharging furnaces comprising a housing
having an opening at its lower portion, a
rockable shaft in said housing, a charge re-
ceiver mounted upon said shaft to rock
25 therewith, means for rocking said shaft
whereby to dump a charge from the receiver
through the opening, and means for locking
the shaft against movement.

19. An apparatus of the class described
30 comprising a housing, a rockable shaft
therein, a charge receiver mounted upon
said shaft, and a guard device underlying
said receiver.

20. A furnace charging and discharging
35 apparatus comprising a housing having a
discharge opening at its lower portion, a
charge receiver arranged within said hous-
ing, and means for guarding said receiver
from drafts of air from said opening.

40 21. An apparatus of the class described
comprising a charge receiver, and a guard
device underlying the same and spaced
therefrom, said guard device being con-
structed and arranged to protect said re-
ceiver from drafts of air.

22. An apparatus of the class described
comprising a rockable shaft, a guard de-
vice secured thereto, supporting means
50 mounted upon said guard device, and a
charge receiver carried by said supporting
means.

23. Apparatus of the class described com-
prising a rockable shaft, brackets secured
55 thereto, an elongate guard trough resting
upon said shaft and secured to said brackets,
supporting means mounted within said
guard trough, and a charge receiver carried
by said supporting means.

24. An apparatus of the class described
comprising an elongate guide, a charge re-
ceiver movable longitudinally of said guide,
and means for supporting said guide to rock
about an axis substantially parallel to its
length.

25. An apparatus for use in charging and

discharging furnaces comprising a receiver,
an elongate bar secured thereto, means pro-
viding a guideway for slidably engaging
said bar, means for imparting movement to
the bar along the guideway, and means for
70 supporting said guideway forming means
whereby the latter may be rocked about an
axis substantially parallel to its length.

26. An apparatus of the class described
comprising a receiver, an elongate bar se-
cured thereto, a pair of parallel guide rails
spaced to provide a guideway for the bar, a
rockable shaft, and means for securing said
guide rails to said shaft whereby said rails
may be rocked about the axis of the shaft. 75

27. An apparatus of the class described
comprising a rockable shaft, a guard trough
secured to the shaft, a pair of parallel rails
secured within said trough and spaced to
provide a guide slot, an elongate bar slid-
80 able within said slot, a charge receiver fixed
to said bar, means for imparting longitudi-
nal sliding movement to said bar, and means
for rocking the shaft.

28. An apparatus of the class described
comprising a rockable guard trough, a re-
ceiver arranged within said trough and slid-
able longitudinally thereof, means for rock-
ing the guard trough, and means for pre-
venting the receiver from falling from the
trough upon rocking of the latter. 90

29. An apparatus of the class described
comprising an elongate trough, a pair of
spaced elements extending lengthwise of
said trough and forming a guide slot, a
charge receiver having a member slidably
engaging said slot, means whereby the trough
may be rocked, and straps overlying said
charge receiver for preventing escape of
said slidable member from the guide slot 100
during rocking of the trough.

30. In combination, a furnace having a
heating chamber, fixed guide means within
said chamber, guide means outside the heat-
ing chamber and normally aligning with
110 said fixed guide means, a charge receiver
having an element engageable with the re-
spective guide means, and means supporting
the guide means outside the furnace so con-
structed and arranged as to permit moving
of such guide means out of alignment with
the guide means in the furnace. 115

31. In combination with a furnace having
a heating chamber and a charging door,
means providing a guide slot within the
chamber and extending inwardly from said
door, a rockable shaft journalled outside
said furnace and substantially in the verti-
cal plane of said guide slot, means carried
by said shaft and providing a guide slot
normally aligning with said first slot, a
charge receiver having an element slidably
engageable with the respective slots, and
means for rocking said shaft whereby to
dump the contents of the receiver when said
120

8
element is in engagement with the guide slot carried by the shaft.

32. In combination with a furnace having a heating chamber and a door giving access thereto, a pair of spaced guide rails leading inwardly from the door, a rockable support outside said furnace, a pair of spaced guide rails mounted upon said support, means for rocking said support, and means normally retaining said support in a position such as to align its guide rails with those within the furnace.

33. In combination with a furnace having a heating chamber, guide means therein, guide means outside the furnace normally aligned therewith, a bar engageable with the respective guide means, a charge receiver carried by the bar, and means for imparting longitudinal movement to said bar in either direction at will.

34. In combination with a furnace, having a heating chamber and guide means therein, an elongate bar engageable with said guide means, a charge receiver fixed to said bar, and means engaging one extremity of said bar for imparting longitudinal movement in either direction thereto.

35. In combination with a furnace, a charging apparatus comprising guide means, an elongate bar engaging said guide means, a charge receiver mounted upon said bar, and cable means secured to that end of the bar remote from the furnace for imparting movement to the bar in either direction.

36. A charging apparatus for furnaces comprising an elongate guide, a bar slidably engaging said guide, a charge receiver mounted upon said bar, a rotatable drum, a cable passing about said drum and having one end thereof secured to one end of said bar, and means connecting the opposite end of said cable with the bar, the parts being so constructed and arranged that rotation of the drum in either direction will move the bar correspondingly.

37. In combination with a furnace having a door, guide means associated therewith, a bar slidably engageable with the guide means, charge receiving means secured to the bar, a rotatable drum, a cable passing about the drum and having one end thereof secured to that end of the bar remote from the furnace door, a second cable connected to the same end of the bar and passing about a pulley arranged adjacent to the furnace door, and means for imparting movement from the other end of the first-named cable to the second cable.

38. Furnace charging apparatus comprising a slidable bar having a charge receiver mounted thereon, a motor driven drum, a cable passing about the drum and having one end secured to one end of said bar, a second cable having its ends secured to the bar, adjacent to the aforesaid end thereof,

and comprising runs extending longitudinally of the bar and at either side thereof, said runs passing respectively over pulleys remote from the drum, and the central portion of said second cable passing about a floating pulley, and means connecting the last-named pulley to the opposite end of the first-named cable.

39. In combination with a furnace, charging apparatus comprising a charge receiver movable into and out of the furnace, motor means for moving such receiver in one direction, and automatic means for stopping the motor at the end of a predetermined movement of the charge receiver.

40. Furnace charging means comprising a movable charge receiver, motor means for moving said receiver in either direction, and automatic means for stopping said motor after a predetermined movement of such charge receiver in either direction.

41. In combination with a furnace, charging apparatus comprising a receptacle slideable into and out of the furnace, a reversible electric motor for moving said receptacle in either direction, switches for controlling said motor, and means actuatable in time with the movement of said receptacle for opening one or the other of said switches at the conclusion of a predetermined movement of the receptacle, in either direction respectively.

42. A furnace charging apparatus comprising a slideable receptacle, guide means therefor, a motor actuated drum, a cable passing over said drum for imparting movement to said receptacle, switch means for controlling the motor, and a member secured to the cable for throwing the switch means to open position after a predetermined movement of the receptacle.

43. An apparatus of the class described comprising a slideable receptacle, a rotatable drum, a reversible motor for actuating the drum, a cable having its central portion passing over the drum and serving to transmit movement therefrom to the receptacle in either direction, a pair of switches for controlling rotation of the motor in either direction respectively, each of said switches having a tail member provided with an opening for the passage of the opposite end portions of the cable respectively, and buttons secured to such portions of the cable and operative by contact with the respective switch tails whereby to move such switches to open position.

44. In combination with a furnace having a door, charging apparatus comprising a movable charge receiver, motor means for moving said receiver into the furnace, and means for preventing actuation of the motor except the furnace door be in open position.

45. In combination a furnace having a

- door, manually actuatable means for opening and shutting said door, a charge receiver, a motor for moving said charge receiver into and out of the furnace, switch means for controlling said motor, and means associated with the door actuating means for preventing closing of the switch means to start the motor except the furnace door be in open position.
46. In combination, a furnace having a door, a charge receiver movable into and out of the furnace, a motor for moving the receiver, a switch for controlling the motor, a slide bar having a lug normally operative to prevent closing of the switch, and means connecting said bar with the door whereby upon opening of the latter the lug is moved to permit closing of the switch.
47. In combination with a furnace having a slidable charging door, a charge receptacle movable into and out of the furnace, power actuated means for moving said receptacle, a manually operable controlling device for said power actuated means, a manually movable element for opening and closing the furnace door, and means for preventing actuation of the first-named manually operable device except when said manually movable element occupies a predetermined position.
48. In combination with a furnace having a door, a charge receptacle movable into and out of the furnace, a reversible electric motor for moving said receptacle, a switch board having a pair of motor controlling switches thereon, a bar slidably guided on said board and having a pair of lugs normally positioned to prevent closing of either switch, and a cable connecting said bar with the furnace door, said parts being so constructed and arranged that upon manipulation of the cable to open the furnace door, the lugs are so moved as to permit closing of either switch.
49. A furnace charging and discharging apparatus comprising, in combination a furnace having a door, a housing constructed and arranged to hood the furnace door, a charge receiver therein, means for depositing a charge in said receiver, means for moving the loaded receiver into the furnace and for withdrawing it therefrom, a quenching tank, means for dumping the charge from the receiver directly into said tank, and automatic means for removing the material, after quenching, from the tank.
50. A furnace charging and discharging apparatus comprising in combination a heat insulated housing constructed and arranged to hood a furnace door, said housing having receiving and discharging openings in its walls, means normally closing said openings, a charge receiver normally positioned within the housing but movable into the furnace, means associated with the receiving opening for holding a charge for delivery into the receiver, means for moving the receiver into and out of the furnace, means for simultaneously opening the discharge opening and for dumping the receiver, means for guarding the receiver from drafts when such opening is opened, a quenching tank arranged to receive the charge from the discharge opening, and means for removing the quenched charge from the tank.
- Signed by me at Taunton, Massachusetts, this eighteenth day of March 1922.
- HARRY B. EATON.
